[57] **CLAIM**

The ornamental design for portable temperature controlled container, as shown and described.

DESCRIPTION

FIG. 1 is a perspective view of a portable temperature controlled container showing my new design;

FIG. 2 is an enlarged top plan view thereof;

FIG. 3 is a greatly enlarged fragmentary sectional view taken along the line 3—3 in FIG. 2 to show surface characteristics of the lid of the container;

FIG. 4 is an enlarged front elevational view thereof;

FIG. 5 is an enlarged right side elevational view thereof;

FIG. 6 is an enlarged rear elevational view thereof; and

FIG. 7 is an enlarged bottom plan view thereof.
